(57) CLAIM

I claim the ornamental design for a combination purse and coat holder, as shown.

DESCRIPTION

FIG. 1 is a top, front and left side perspective view of a combination purse and coat holder showing a first embodiment of my new design;

FIG. 2 is a front elevational view thereof;

FIG. 3 is a rear elevational view thereof;

FIG. 4 is a right side elevational view thereof;

FIG. 5 is top plan view thereof;

FIG. 6 is a bottom plan view thereof;

FIG. 7 is a top, front and left side perspective view of a combination purse and coat holder showing a second embodiment of my new design;

FIG. 8 is a front elevational view thereof;

FIG. 9 is a rear elevational view thereof;

FIG. 10 is a right side elevational view thereof;

FIG. 11 is top plan view thereof; and,

FIG. 12 is a bottom plan view thereof.
